BATH SEAT

Benjamin A. Gay, 72 S. Forge Manor Drive,
Phoenixville, Pa.
Filed Apr. 16, 1964, Ser. No. 360,378
2 Claims. (Cl. 108—134)

The present invention relates to a bath seat and more particularly to a bath seat assembly which is mechanically operated. The present bath seat assembly is adapted to use in standard bath tubs and may be compactly folded into an inconspicuous cabinet when not in use.

The bath seat of the present invention comprises a seat member, a pair of supporting arms attached to opposite edges of the seat member, a pair of spaced rollers positioned on one side of each supporting arm along the portion of the arm positioned farthest from said seat member, and a vertical guide means having at least one pair of parallel contact surfaces. One pair of the spaced rollers is positioned in contact with each pair of parallel contact surfaces. Suitably the vertical guide means consists of a pair of vertical guide rails. In a preferred embodiment of the present invention one pair of each pair of the spaced rollers is positioned astraddle each of the parallel guide rails. Preferably the present bath seat assembly includes a cross-member mounted between the supporting arms and includes a raising and lowering means attached to the cross member to raise and lower the seat. The present assembly may also include a mounting plate having the guide rails mounted thereon and in spaced relation thereto.

In a preferred embodiment of the present invention the uppermost portion of the vertical guide rails are off-set in a direction away from the mounting plate. The supporting arms may also have an off-set therein. The arms are suitably off-set along a portion of the supporting arms located farthest from the seat member and are off-set in a direction toward the guide rails.

The present invention will best be understood by reference to the accompanying drawings which show preferred embodiments of the present invention and in which similar components are identified by similar numbers throughout each of the several views. FIGURE 1 is a prospective view of the bath seat assembly of the present invention which includes a raising and lowering mechanism. FIGURE 1 also shows an embodiment of the invention wherein the seat member is moveable in a sidewise manner. FIGURE 2 is a prospective view of a typical bathroom containing a bath tub equipped with a bath seat similar to that shown in FIGURE 1. FIGURE 3 is a prospective view of a portion of a guide rail showing an alternate means of supporting the seat member along two contact surfaces located within the guide rails.

Referring now to FIGURE 1 in detail, a rigid frame 11, preferably fabricated of a metal such as steel, provides support for a pair of generally parallel, spaced guide rails 13 and 13' spaced from frame 11. Suitably frame 11 and rails 13 and 13' may be a single component or, as illustrated, rails 13 and 13' may be attached to and spaced from frame 11 by means of spacers 15, 15', 17 and 17'. Spacers 17 and 17' may also serve as stops to fix the lowermost position of the bath seat 19. Bath seat 19 is equipped with generally parallel supporting arms 21 and 21' attached thereto by hinge members 23 and 23'. A pair of spaced rollers 24 and 24' are mounted on arm member 21' so that roller 24 is located on one side of guide rail 13 on contact surface 26 and roller 24' is located on the opposite side of arm 21' on contact surface 26'. Arm member 21 is equipped with roller members 25 and 25' so that one member of the roller pair is on one side of arm member 21 on contact surface 28, and

2

the other member of the roller pair is positioned on the opposite side of arm member 21 on contact surface 28'. Roller members 24, 24', 25 and 25' in contact with the contact surfaces of guide rails 21 and 21' support seat member 19 at a fixed angle to the guide rails and allow the seat member to be raised and lowered while so supported. As shown in FIGURE 1, guide rails 13 and 13' have off-set portions 27 and 27'. The off-set portions 27 and 27' of the guide rails allow a vertical alignment of the seat supporting arms and the guide rails when the roller members 24' and 25' pass over the off-set portions of the guide rails. Suitably supporting arms 21 and 21' may also be equipped with off-set portions 22 and 22', off-set in a direction generally toward guide rails 13 and 13'. The latter off-set combined with the previously described off-set in the guide rails facilitates easy vertical alignment of supporting arms 21 and 21' and guide rails 13 and 13'. A cross member 31 is positioned between seat supporting arms 21 and 21'. A suitable raising and lowering means 29 is connected to move the seat support arms, preferably through a connection to the cross member 31 by a suitable linkage 33. Linkage 33 connects the motivating source 29 with the seat assembly and may, for example, be a cable, a rod, or a screw. The raising and lowering means may be operated by any suitable available energy source, for example, electrical, pneumatic, or hydraulic sources are suited to perform the raising and lowering operations. Preferably a suitable control for the raising and lowering means is located at a position convenient for the user of the bath seat. However, a remote control may be desirable from a safety standpoint and may easily be adapted to the present device. If the raising and lowering means 29 is electrically operated, it is preferred for safety purposes to use a low voltage relay control system. A 6 to 12 volt control circuit is aptly suited for this purpose.

As shown in FIGURE 1, the bath seat assembly of the present invention may be mounted to provide horizontal movement of the seat member to facilitate entry to and exit from the bath tub by the user by means of a mounting frame 37 and a pivoting means, such as hinges 39 and 39' positioned between frame 37 and base plate 11. This arrangement allows base plate 11 with the appended seat member to pivot about hinge members 39 and 39' so that seat member 19 may be moved horizontally from a position directly over a bath tub to a position of chair height above the floor and to one side of the bath tub.

FIGURE 2 shows a view of the bath seat of the present invention embodied in a mounted cabinet and installed in a typical bathroom. The dashed lines represent the bath seat as shown in FIGURE 1 in position to be used. FIGURE 2 shows a seat-cabinet unit 41 installed on wall 45 over bath tub 47 in a typical bathroom.

The lower front portion of cabinet 41 is the bottom of the base portion of seat 19. The seat support arms and guide rails have been vertically aligned as described above, allowing compact storage of the entire assembly within the confines of cabinet 41. Cabinet 41 is suitably hinged to a mounting frame 37 to allow horizontal movement of the bath seat when the seat is in an extended position. A suitable control means, for example, switch 49 may be positioned at any convenient location, for example, along wall 45 to operate the raising and lowering means. FIGURE 3 shows an alternate means of supporting the seat member along the guide rails. FIGURE 3 is a view of a portion of a guide rail 30 having an elongated slot 32 therein. Slot 32 has parallel contact surfaces 34 and 34'. In this embodiment rollers 24 and 24' are positioned within the confines of slot 32 and in contact with contact surfaces 34 and 34' of guide

rail 30. This arrangement allows supporting arm 21 to move vertically at a fixed angle to guide rail 30.

The present assembly is preferably fabricated of corrosion-resistant materials. Stainless steel is particularly suited to use in the present devices.

What is claimed is:

1. A bath seat comprising
a seat member, having a pair of opposite edges,
a pair of supporting arms attached to said opposite
edges of said seat member,
a pair of spaced rollers positioned on each supporting
arm along the portion of said arms positioned far-
thest from said seat member,
a pair of spaced vertical guide rails each of said ver-
tical guide rails having one pair of said rollers posi-
tioned astraddle thereof and in contact therewith,
said seat member being held immovable in a hori-
zontal plane and movable in a vertical plane by the
contact of said rollers and said vertical guide rails.
2. A bath seat comprising
a seat member, having a pair of opposite edges,
a pair of supporting arms attached to said opposite
edges of said seat member,
each supporting arm having a pair of spaced rollers
positioned on one side thereof along the portion
of said arm located farthest from said seat member,
a pair of spaced vertical guide rails, each of said ver-

tical guide rails having one pair of said rollers posi-
tioned astraddle thereof, and in contact therewith,
said seat member being held immovable in a hori-
zontal plane and movable in a vertical plane by the
contact of said rollers and said vertical guide rails,
said vertical guide rails mounted in spaced relation on
a mounting plate,
said vertical guide rails having an off-set portion in
the uppermost portion thereof in a direction away
from said plate.
